TORPEDO

Original Filed April 27, 1921

Patented July 19, 1927.

1,636,307

UNITED STATES PATENT OFFICE.

CHARLES KESSES, OF NEW YORK, N. Y.

TORPEDO.

Original application filed April 27, 1921, Serial No. 464,949. Divided and this application filed July 8, 1926. Serial No. 121,148.

This is a divisional application of my application for a signal clock, filed April 27, 1921 Serial No. 464,949, and is related to my applications signal clocks, filed Sept. 7, 5 1921 Serial No. 499,066 and Serial No. 756, 262 filed Dec. 16, 1924 and to application flying torpedo filed June 23, 1926, Ser. 118, 005. The co-operation of the several parts 10 throughout a complete circle of movements involved for operating the flying torpedo or manless aeroplane is specified first, in my original specification filed April 27, 1921 in two complete pages, page 14 and page 15 and second in my amendment for the same 15 application March 21, 1925, page 3, line 14, inclusive to page 5, line 10.

This invention relates to certain improvements in flying torpedoes and the objects are—

20 First, to have a torpedo arranged in an aeroplane.

Second, to have an engine or a motor provided for driving a propeller to fly said torpedo.

25 Third, to have a signal clock arranged in said flying torpedo regulating means on said signal clock, to explode an explosive at any predetermined time.

Fourth, to have an operating lever provided to start or to stop the operation of the electric clock.

In the accompanying drawings the device of my invention is fully illustrated.

Fig. I is a view of a half cut of the flying torpedo, shown from above.

Fig. II is a side view of the entire electric clock.

Fig. III is a perspective front view of the switches, which are arranged for moving to various selective positions on the dial.

Similar numbers refer to similar parts throughout the several views.

A member 1 constitutes the framework of the flying torpedo, its wings 2 are secured in a suitable manner to the upper part of said member. A powerful engine or an electric motor 3 for driving a propeller 4 is secured in said member. Either one of an engine or a motor can be used, the one which will be best suitable for lightness and strength to fly said torpedo for a short distance.

A signal clock 5 for operating said torpedo is secured to the member 1 in such a position to extend its dial 6 with its switch

7 out of an opening in the rear of said member. A lever 8 for operating said clock must extend out of said member to be in easy reach to the operator. An explosive 9 and a storage battery 10 must be secured in the bottom of said member in such a manner and position to balance the torpedo in every direction.

A second view of the signal clock 5 is being shown in Fig. II. Said clock is provided with the dial 6 which is with its upper part secured to the member 1. The switches 7, a separate view of which is shown in Fig. III, are movably arranged on the dial 6, said switches consisting of a member 12 which carries the contacts 14 and 15. Said member is provided with a screw 16 to secure said member to different positions on the dial 6. A second member 17 carries the contacts 18 and 19 and is secured with a pin 20 in the centre of said first named member in such a manner to close the circuit between the contacts 15 and 19 by the forward moving of said second member and to open said circuit thereby closing the circuit on the contacts 14 and 18 by moving said second member in the opposite direction. A spring 21 secured on both of said members to give said second member a fixed position.

A member 22 is provided for carrying said switches and to hold in its inner side the electric current, conduits for the current to and the return current from said switches in a straight position, the other end of said member is arranged on the main-shaft 23 of the clockwork. A frame or stand 24 is secured in the rear of the dial to the member 1 in such a position to allow the turning of the switch carrying member 22 around the dial 6. Grooves are arranged in a hard rubber plate in the stand 24 for holding circular current contacts 25 and 26 for the current to and contacts 27 and 28 for the return current from said switches. Contacts 29, 30, 31, and 32 are secured in the switch carrying member 22 in such a position to press on and be in contact, one each of said contacts with one of the circular contacts 25, 26, 27 and 28 wherever the switch 7 is moved.

Electric current conduits are arranged in the inner part of the switch carrying member 22 in the following manner, one conduit 32^a to close the circuit between the switch-contact 14 and the contact 29 in the

switch member 22, a conduit 32^b between the switch contact 19 and the contact 30, a conduit 32^c between the switch contact 18 and the contact 31 and a conduit 32^d between the switch contact 15 and the contact 32. Corresponding openings 33 are arranged in the first and the second switch members to provide means to lead the conduits which are arranged on the switch contact 18 and 19 in the second switch member 22 to the inner part of the first switch member 12.

The clockwork which operates the electric device being connected through the shaft 23. Said shaft is in two parts, 23^a and 23^b. A clutch 34 is secured to the shaft 23^a and is meshed to a clutch 35 which is slidably arranged on the shaft 23^b. A rail 36 secured to said shaft is fitted in a corresponding opening in the clutch 35 to connect or to disconnect both shafts. A lever 8 is secured to said clutch to connect the clock mechanism to the electric switch device at the will of the operator. The clockwork which operates the electric device being connected through the shafts 23^a and 23^b. One part of said clock is a paddle wheel 38, the size of the paddles must be in proportion to give the right air-resistance for the movement of the hand 39 around the dial required, at the lower part of said clockwork is a spring or a weight 40. A chain of gears and pin wheels connect said paddle-wheel with said spring. A spring 41 is secured to the shaft 23^a and to the member 1 to return the hand 39 when the same is released from the clutch 35 to its fixed position at a pin 42.

The electric circuits from the storage battery 10 to the electric switch device and the circuits from said device to the motor 3 and the explosive 9 are as follows: two separate conduits 43, one for the negative current and one for the positive current from said storage battery to a main switch 44. A conduit 45 to close the circuits for the positive current between said main switch and the circular contacts 25 and 26. A conduit 46 to close the circuits for the negative current between said main switch and the motor 3 and to a suitable electric device to explode the explosive 9. A conduit 47 to close the circuit between the switch 15-19 and said motor 3 and a conduit 48 between the switch 14-18 and said suitable electric device. Said explosive can also be exploded with the signal clock by securing the conduits 48 and 46 together in a powder charge.

Now the co-operation of the several parts throughout a complete circle of movements

involved in the operation of the flying torpedo; set the switch 7 to determine time to 60 explode the explosive 9, close the switch 44 to close the circuit of the negative current to the suitable electric device which explodes the explosive 9 and to the motor or engine 3, pull the operating lever 8 thereby connecting the clock mechanism to the electric switch device, with the clutches 34 and 35, the positive current is led through the switch 15-19 thereby starting the propeller 4, the hand 39 is moved by the clockwork for the 65 indicated time set, to move with said hand the second switch member 17, to open the circuit on the switch 15-19 and closing the circuit on the switch 14-18 to explode the explosive 9. 70

I am aware that prior to my invention torpedoes have been used but I have never seen one which had wings for flying said torpedo, or a motor or a gas engine for driving a propeller for said torpedo or an explosive which can be exploded at a predetermined time. 75

What I claim as my invention and desire to secure by Letters Patent is:—

In a flying torpedo, in combination, wings 85 arranged on said torpedo, a propeller mounted to propel said torpedo, a motor arranged to drive said propeller, an explosive charge 90 arranged in said torpedo, a source of electric power, a timing device for exploding said explosive at a predetermined time; said timing device consisting of a shaft, an arm rotatable with said shaft, a pivoted contact member in the path of said arm, said member having contact elements mounted on each 95 side thereof, the contact elements on one side being normally closed and the contact elements on the other side being normally open; a main switch mounted on said torpedo, an electric circuit including the source of power, 100 the main switch, the driving motor and the said contact elements which normally remain closed, a second circuit including the source of power, the main switch, the explosive charge and the said contact elements 105 which normally remain open; a clockwork for driving the said shaft of the timing device, a clutch interposed between said clockwork and said shaft and a manually operated lever for engaging said clutch, the driving motor and timing device being started in operation by the closing of the main switch and the engaging of said clutch by movement of said lever. 110
